Claims priority, application Sweden Jan. 2, 1958

Term of patent 14 years

(Cl. D49—1)

Fig. 1 is a perspective view of a washing machine showing my design, the rear being substantially plain and the side not shown being the same as the side shown except for the element indicated in broken line;

Fig. 2 is a front elevational view thereof;

Fig. 3 is a side elevational view thereof;

Fig. 4 is a top plan view thereof; and

Fig. 5 is an enlarged fragmentary sectional view taken at line 5-5 of Fig. 2.

The dominant features of my design reside in the portions shown in full lines.

I claim:

The ornamental design for a washing machine, as shown and described.
